US00D918195S

(12) **United States Design Patent** (10) Patent No.: **US D918,195 S**
(45) Date of Patent: ** May 4, 2021

(54) **ALL-IN-ONE COMPUTER**

(71) Applicant: **Lenovo (Beijing) Co., Ltd.**, Beijing (CN)

(72) Inventor: **Shujie Dong**, Beijing (CN)

(73) Assignee: **Lenovo (Beijing) Co., Ltd.**, Beijing (CN)

(**) Term: **15 Years**

(21) Appl. No.: **35/507,742**

(22) Filed: **Jul. 11, 2019**

(80) **Hague Agreement Data**

Int. Filing Date: **Jul. 11, 2019**

Int. Reg. No.: **DM/203992**

Int. Reg. Date: **Jul. 11, 2019**

Int. Reg. Pub. Date: **Nov. 15, 2019**

(30) **Foreign Application Priority Data**

Jan. 11, 2019 (CN) 201930016053.6

(51) **LOC (13) Cl.** **14-02**

(52) **U.S. Cl.**

USPC **D14/307**
